(57) **CLAIM**

The ornamental design for an automobile body, as shown and described.

DESCRIPTION

FIG. 1 is a frontal perspective view of an automobile body showing our new design;

FIG. 2 is a rear perspective view thereof;

FIG. 3 is a side elevational view of one side thereof;

FIG. 4 is a side elevational view of the other side thereof;

FIG. 5 is a front elevational view thereof;

FIG. 6 is a rear elevational view thereof; and,

FIG. 7 is a top plan view thereof.

The broken line showing of the wheels, tires, front grille, rear-view mirrors, door handles, fuel door, exhaust pipes, sunroof and license plate mounts is for illustrative purposes only and forms no part of the claimed design.
